UNITED STATES PATENT OFFICE.

CHARLES GIFFORD, OF GARDINER, MAINE.

CAR-CO尤LING.

SPECIFICATION forming part of Letters Patent No. 236,943, dated January 25, 1881.

Application filed November 8, 1880. (No model.)

To all whom it may concern:

Be it known that I, CHARLES GIFFORD, of Gardiner, county of Kennebec, State of Maine, have invented a new and useful Improvement 5 in Car-Couplings, of which the following description, in connection with the accompanying drawings, is a specification.

This invention relates to improvements in car-couplings, and has for its object to provide 10 the coupling with a link-operating device which shall positively overturn the link or tip it over forward from its elevated position back of a vertical line, so that it will be thrown into engagement with the hooked head 15 or link-engaging projection of an opposed draw-bar.

In my invention each draw-bar is shown as provided with a link-engaging projection to be caught by the link of an opposed draw-bar, 20 and each draw-bar, in a suitable recess at the rear of its projection, receives a link provided with suitable guides, which, co-operating with the draw-bar, prevent the link from being turned in the direction of its circumference. 25 Each draw-bar is provided with a link-operating device, which is so held or mounted thereon that it, when the ends of the draw-bar meet or come together, will be operated to positively turn the link of one of the draw-bars 30 forward from its upright position, it being thrown over and down, so as to catch the link-engaging projection of the opposite draw-bar and couple the cars together.

Figure 1 represents, in side elevation, the 35 front end of a draw-bar with its coupling-link elevated, that being the position it will occupy when the cars to be coupled are approaching each other, and the draw-bars strike together at their ends. Fig. 2 is a side elevation, showing the forward portions of two draw-bars of adjacent cars, one coupling-link being shown in position to couple the draw-bars together, the other coupling-link, not then to be brought 40 into use, being shown as hanging down and broken off at its lower end, the latter being to save room on the drawings; and Fig. 3 is a top view of Fig. 2, the draw-bar at the right of such figure being omitted.

The draw-bars a b' are supposed to be alike, 45 so I need not herein describe with particularity more than one of them. Each draw-

bar has a link-engaging projection, b or b' , to be engaged by a coupling-link, c or c' , as in Fig. 2, to couple together the two draw-bars and the cars with which they are connected. 55 At the rear of each link-engaging projection there is a recess or seat, d , for the link. Each side of each link has connected with it two guide-arms, e , which act against the outer sides of the draw-bar, compelling the link, in 60 its movements, to turn only in the arc of a circle about its bearing or seat in the said recess d , the link moving only in the arc of a circle about a horizontal center; or, in other words, the guides, acting against the sides of the 65 draw-bar, prevent the link from being moved in the direction of its circumference or in the direction of the arrows, Fig. 3. Each draw-bar has a stop, f , which arrests the descent of the link when turned down, as at the right of 70 Fig. 2.

At the top of each draw-bar I have made a groove, g , in which I have placed the shank of the link-operating device, it being composed of a sliding bar, h , provided with a suitable cross-head, i , or pusher, against which the link will preferably rest when elevated or turned back, as in Fig. 1, wherein the link is shown in the position it will occupy when it is about to be operated or thrown from a position at the rear 80 of a vertical line forward and down into engagement with the projection b' of an opposed draw-bar on another car. This link-operating device h , in order to prevent the link escaping from the recess d , has its front end, 2, prolonged beyond the cross-head i into a recess made in the draw-bar below the projection b or b' , as indicated by dotted lines in Figs. 1 and 2, extended forward to near the front ends of the draw-bars. The link-operating device 85 h has a lug, 3, which, when the link c is elevated, as in Fig. 1, and the cross-head is drawn back ready to be operated to throw the link forward, 90 stands at the rear of the ears 4, which form parts of the draw-bar. 95

When the ends of the draw-bars abut or strike together, the draw-bars are each made to recede one or more inches backward under the platform of the car, and in so doing the projection 3, striking against a fixed part of the car or platform—as, for instance, the fixed part designated by the letter l in Fig. 1—will 100

cause the link-operating device to travel forward in its groove in the draw-bar as the draw-bar recedes for this short distance, such movement of the link-operating device causing the cross-head *i* at the rear of the link *c* (see Fig. 1) to act quickly against the said link near its lower end or near its bearing in the recess *d*, instantly throwing the link positively forward and downward toward, and so as to engage, the opposing part *b'* of the draw-bar *b*², or throwing the said link from its position, Fig. 1, into the position, Fig. 2, thus coupling the draw-bars and cars together.

I might use one or more guides *e* to prevent the link moving in the direction of the arrows, Fig. 3, or, as I have called it, circumferentially.

I claim—

1. In a car-coupling, the link *c*, loosely held in a recess in the draw-head, and provided with the projections *e*, to prevent lateral or circumferential movement and longitudinal displacement of the link, substantially as described.

2. In a car-coupling, the draw-bar provided with a link-engaging projection, and with a recess to receive one end of the link and per-

mit it to be turned from one to the other side of a vertical line at right angles to the draw-bar, and a link provided with lateral guides 30 and mounted in said recess, combined with a reciprocating link-operating device having a cross-head to act upon the said link, near its lower end, and throw it positively upward, forward, and down over the link-engaging projection of an opposed draw-bar, substantially as described.

3. In a car-coupling, a draw-bar provided with a recess, *d*, to receive one end of the link, and the link *c*, provided with guides *e*, and 40 mounted in the said recess, combined with the link-operating device provided with a cross-head to throw the link forward, and with a forward projection, 2, to bridge over the said recess and retain the end of the link therein, 45 substantially as described.

In testimony whereof I have signed my name to this specification in the presence of two subscribing witnesses.

CHAS. GIFFORD.
